CARD TABLE ATTACHMENT

Nell Ritch, San Antonio, Tex.

Application May 11, 1934, Serial No. 725,195

2 Claims. (Cl. 311—103)

This invention appertains to new and useful improvements in furniture, and more particularly to a novel card table attachment.

The principal object of the present invention is to provide a card table having a novel pencil rest located toward one side of each player's position at the table.

Another important object of the invention is to provide a pencil rest for card tables which is 10 of simple construction and of low cost to manufacture.

These and various other important objects and advantages of the invention will become apparent to the reader of the following specification.

15 In the drawing:

Figure 1 represents a top plan view of the table equipped with a pencil rest at each corner thereof.

Figure 2 represents a bottom plan view of one corner portion of the table.

20 Figure 3 represents a sectional view taken substantially on line 3—3 of Figure 1.

Referring to the drawing wherein like numerals designate like parts, it can be seen that numeral 5 represents the table top and numeral 6 generally refers to one of the novel pencil rests.

The pencil rest consists of an elongated trough-like structure 7 constructed of sheet metal and provided with lateral flanges 8 at its upper portion for rest upon the top side of the table, while 30 the trough proper depends through an opening 9 in the table. The bottom of the trough depends a substantial distance below the bottom

side of the table top and several retaining cross members 10 can be spot-welded to the bottom of the trough. These cross members are preferably arcuate and also are preferably of spring metal so that their ends will tensionally bear against the under side of the table top.

5 While the foregoing specification sets forth the invention in specific terms, it is to be understood that numerous changes in the shape, size and materials may be resorted to without departing 10 from the spirit and scope of the invention as claimed hereinafter.

Having described the invention, what is claimed as new is:—

1. In combination, a table top having a slot 15 therein, an elongated trough structure for snug disposition in said opening, and a member secured to and extending across the bottom of the trough and having end portions bearing against the bottom side of the table top to retain the 20 trough in said opening.

2. In combination, a table top having a slot 25 therein, an elongated trough structure for disposition in said opening, a member secured to and extending across the bottom of the trough and having end portions bearing against the bottom side of the table top to retain the trough in said opening, said portions being bent arcuately and having spring tension so as to tensionally bear against the bottom side of the table top to snugly 30 retain the trough in said opening.

NELL RITCH.
